UNITED STATES PATENT OFFICE.

CHARLES C. BADGLEY, OF NEELYSVILLE, MISSOURI.

STEAM LOGGING-CRAB.

SPECIFICATION forming part of Letters Patent No. 270,873, dated January 16, 1883.

Application filed November 20, 1882. (No model.)

To all whom it may concern:

Be it known that I, CHARLES C. BADGLEY, of Neelysville, Butler county, Missouri, have made a new and useful Improvement in Crabs, 5 of which the following is a full, clear, and exact description, reference being had to the annexed drawings, making part of this specification, in which—

- Figure 1 is a side elevation, and Fig. 2 a plan.
10 The same letters denote same parts.
The present device is useful in many classes of work wherein crabs and winches are used. It is, however, especially adapted to logging purposes, for it enables logs to be readily drawn 15 from any quarter, and frequently from points and across places where it is impracticable to employ teams in moving the logs. The prominent feature of the construction is a drum constructed to be turned to and to wind from any 20 quarter of the horizon, to which end the drum is mounted upon a turn-table and the turn-table is pivoted in a base. The drum is divided, one end of the drum receiving one rope and the other end of the drum receiving another rope, and as 25 one of the ropes is being wound onto one end of the drum the other of the ropes is being unwound from the other end of the drum. The drum is preferably actuated by steam-power, the engine or engines and boiler being mounted 30 with the drum upon the turn-table and rotating therewith. The entire construction is thus self contained, and as such can be transported from place to place, as desired. The base is preferably made so that when it is desired to 35 move the crab the rope can be attached to an object in the direction in which the crab is to be moved, and then by winding the rope onto the drum the base and superstructure are drawn along.
40 The preferable mode of carrying out the improvement is illustrated in the drawings, in which A represents the drum, B the turn-table, and C the base. The drum-shaft a turns in the bearings a' a'' , which are attached to the turn-table. By means of the flange a^2 one end, a^3 , of the drum is divided from the other end, a^4 . The drum at its center (which is a convenient place 45 therefor) is also provided with the gear D. A pair of steam-engines, E E', is preferably used.
50 The engines and boiler E² are secured to the

turn-table—that is, in practice the engines are mounted upon a suitable frame, E³, which in turn is secured to the turn-table. The motion of the engine-pistons is communicated to the cranks F F'. The pitmen leading from the 55 engine to the cranks are not shown. Their nature and operation, however, are well understood. The crank-shaft F² is provided with a pinion, F⁴, which engages with a gear, G, upon a counter-shaft, G'. The last-named shaft G' 60 is provided with a pinion, G², which engages with the drum-gear D. The motion of the engines is thus communicated to the drum. Any other suitable mechanism, however, can be used in effecting such communication; but I 65 regard that shown and described the most desirable.

The turn-table B turns upon the shaft B'. (Shown in broken lines in Fig. 2.) The shaft B' is suitably held or fixed in the base C. The 70 rollers H support the turn-table near its periphery. The shaft B' is provided with a gear, I. A vertical shaft, J, having a handle or crank, J', and working in a bearing, J², in the turn-table, is provided with a pinion, J³, which engages with the gear I. By rotating the shaft J the turn-table, together with the drum, engines, &c., is turned toward that quarter from which it is desired to obtain the logs. The crab is then brought into operation, and the 80 rope, which is attached to the log being drawn, is wound onto one end of the drum—say the end a^3 —and the log is drawn up to the crab. The rope upon the other end, a^4 , of the drum is wound thereon in the opposite direction to 85 that of the rope upon the end a^3 , and as the rope is wound, as described, onto the end a^3 the rope upon the end a^4 is unwound therefrom, and as it is unwound it is carried to the log next to be drawn in, and so on, as one log is 90 being moved a rope is being placed in position for moving another log. The capacity of the crab is thus largely increased.

The side rails, c c, of the base C are preferably made in the form of sled-runners to facilitate 95 the moving of the device. The ropes are not shown in the drawings.

I claim—

1. A crab pivoted centrally to its base, to enable the drum to be turned to any quarter.

2. A crab pivoted to its base, and having the drum divided into the parts a^3 a^4 , as and for the purposes described.
3. The combination of the drum A, the gear D, the engines E E', the cranks F F', the shafts F² G', and the gears F⁴ G G², substantially as described.
4. The combination, in a crab, of the turntable B, the base C, the shaft B', the gear I, the shaft J, and the pinion J³, substantially as described.
5. In a crab, a table supporting the drum of the crab and the mechanism for operating the drum, and pivoted to a base beneath the table, for the purposes described.

C. C. BADGLEY.
